UNITED STATES PATENT OFFICE.

AUGUSTUS PLUMMER DAVIS, OF PITTSBURG, PENNSYLVANIA.

DESIGN FOR A BADGE.

SPECIFICATION forming part of Design No. 17,167, dated March 8, 1887.

Application filed August 20, 1886. Serial No. 211,439. Term of patent 7 years.

To all whom it may concern:

Be it known that I, AUGUSTUS PLUMMER DAVIS, a citizen of the United States, and a resident of the city of Pittsburg, county of Allegheny, and State of Pennsylvania, have invented and produced a new and original Design for a Badge for the members of a body called "The Ladies' Aid Societies of the Sons of Veterans of the United States of America," to of which the following is a full description and specification, reference being had to the accompanying drawings, forming part thereof.

Figures 1 and 2 are views of the badge, taken from opposite sides.

On the face of the badge is a medallion with representation of an American eagle. Radiating from the center, behind the eagle, are rays. Between two concentric circles of the medallion is a space for an inscription, the inner circle inclosing the eagle and rays. Surrounding the medallion is a wreath of laurel, the ends of two cannon, which apparently cross

at the back of the wreath and medallion, and the projecting ends of a Greek cross, which ends are of particular design, upon which appear certain letters. Upon the back of the badge is a raised medallion, in the center of which is a space for a monogram and rays radiating from behind the center of the space for a monogram. Surrounding the monogram is the space for an inscription, said inscription being between two concentric circles of the medallion, the inner circle inclosing the monogram and rays.

What I claim is—

The design for a badge, consisting of the medallion, with the representation of the eagle backed by the sun-rays, of the laurel-wreath, the cannon, and the cross, as set forth and shown.

AUGUSTUS PLUMMER DAVIS.
